UNITED STATES PATENT OFFICE

142,761

DESIGN FOR A TRACTOR CAB

Christian Zeiler, Morton, Ill.

Application March 9, 1945, Serial No. 118,383

Term of patent 14 years

(Cl. D14—3)

To all whom it may concern:

Be it known that I, Christian Zeiler, a citizen of the United States, residing at Morton, in the county of Tazewell and State of Illinois, have invented a new, original, and ornamental Design for a Tractor Cab, of which the following is a specification, reference being had to the accompanying drawing, forming part thereof.

In the drawing:

Fig. 1 is a side elevational view of a tractor cab showing my new design;

Fig. 2 is a front elevational view of a tractor cab showing my new design;

Fig. 3 is a rear elevational view of a tractor cab;

Fig. 4 is a top plan view; and

Fig. 5 is a rear perspective view thereof.

I claim:

The ornamental design for a tractor cab, substantially as shown.

CHRISTIAN ZEILER.
